UNITED STATES PATENT OFFICE.

CHARLES B. McBRIDE, OF SEBRING, OHIO.

METALLIC WINDOW SCREEN.

Application filed August 19, 1922. Serial No. 582,972.

To all whom it may concern:

Be it known that I, CHARLES B. McBRIDE, a citizen of the United States, residing at Sebring, in the county of Mahoning and State of Ohio, have invented new and useful Improvements in Metallic Window Screens, of which the following is a specification.

One object of my said invention is the provision of a window screen of adjustable type formed of sheet metal, metallic connections and metallic reticulated members, and hence possessed of great strength and durability and capable of resisting any tendency to warp or get out of shape.

Another object of the invention is the provision of a metallic window screen in which provision is made for the ready replacing of a rusted, worn or broken reticulated member without the employment of skilled labor.

To the attainment of the foregoing, the invention consists in the improvement as hereinafter described and definitely claimed.

25 In the accompanying drawings, forming part of this specification:—

Figure 1 is a front elevation showing my novel window screen as partly extended.

Figure 2 is a top plan view of the same.

30 Figure 3 is a horizontal central section of the screen.

Figures 4 and 5 are detail vertical sections hereinafter explicitly referred to.

Figure 6 is a detail view illustrative of a modification hereinafter explicitly referred to.

Similar numerals designate corresponding parts in Figures 1 to 5 to which reference will first be made.

40 My novel screen is adjustable as to length and includes two members, each member being slidable relatively to the other. The said members respectively comprise a reticulated metallic section 1, an outer end bar 2, horizontal bars 3 and an inner end bar 4, all of the said bars being formed of sheet metal. The outer end bar 2 is hollow and of general rectangular form in horizontal section so as to possess the 45 quality of stiffness and be adapted to slide in a guideway provided at the inner side of the side stile of a window casing, and it is provided with the inner closely arranged flanges 5. The outer ends of the reticulated 50 section 1, and the horizontal bars 3 are interposed between the said flanges 5 and are

connected thereto by rivets 6. The upper and lower horizontal bars 3 are formed of strips of sheet metal folded upon themselves, and the upper and lower edges of the reticulated section 1 are arranged in the folds of the said bars 3 and are guarded and protected by the bars. The inner end bar 4 is also formed of a strip of sheet metal folded upon itself and the inner end of the reticulated section 1 is arranged in the fold of the end bar 4 and is guarded and protected thereby. It will also be observed that one thickness or side of the bar 4 is extended beyond the other thickness or side thereof. 60 The said extended portion of the bar 4 is arranged alongside of and is riveted at 7 to the inner end portions of the horizontal bar 3, and are bent into hooks 8 which are designed to straddle the bars 3 of the other 65 member of the screen so as to connect the members together in side by side relation without interfering with the slideable capacity of the members, though it will be noticed that the hooks 8 of the two members are 70 adapted to prevent one member from being withdrawn endwise out of engagement with other. I also desire it understood that I prefer in practice to cover the sheet metal portions of my novel screen with an appropriate composition baked on the iron with a view to promoting the durability of the screen as a whole. This, however, is not 75 of the essence of my invention and hence it will be understood that the screen or the 80 sheet metal portions thereof may be coated or not in the discretion of the manufacturer.

It will be manifest from the foregoing that a window screen characterized is described as being adjustable as to length without being expensive in construction; also, that the screen is exceedingly strong and durable and at the same time light in weight, and is not liable to warp or sag out of shape.

Instead of employing rivets such as 6 and 7 in the relations described I may employ screws 6^a and 7^a as shown in Figure 6, the said screws being specifically advantageous in that they permit of the bars of the members to be easily disassembled for the ready removal of a rusted, worn or broken reticulated section 1 and the expeditious replacing of such section with a new section. This 95 obviously may be accomplished without the employment of skilled labor and without the 100 employment of any tool other than an ordinary screw driver.

I have entered into a detailed description of the construction and relative arrangement of the parts embraced in the present and preferred embodiments of my invention 5 in order to impart a full, clear and exact understanding of the said embodiments. I do not desire, however, to be understood as confining myself to the specific construction and relative arrangement of parts inasmuch as in the future practice of the invention various changes and modifications may be made such as fall within the scope of my invention as defined in my appended claims.

Having described my invention, what I 10 claim and desire to secure by Letters-Patent, is:—

1. An adjustable metallic window screen comprising two slidable members each held to and movable endwise relative to the 15 other each member made up of an outer sheet metal end bar with a hollow rectangular body and inner side by side flanges integral with said body, a reticulated section with its outer end interposed between the said flanges, upper and lower sheet metal bars attached to the upper and lower edges of the screen section and having their outer ends interposed between and attached to the said flanges of the body, and 20 an inner sheet metal bar attached to the inner end of the reticulated section.
2. An adjustable metallic window screen 25

comprising two slidable members each movable endwise relative to the other, each member made up of an outer sheet metal end bar with a hollow rectangular body and inner side by side flanges integral with said body, a reticulated section with its outer end interposed between the said flanges of the body, upper and lower sheet metal bars 30 folded on themselves and receiving the upper and lower edges of the screen section and having their outer ends interposed between the said flanges, an inner sheet metal bar, folded upon itself and receiving the inner end of the reticulated section and having end portions arranged in lapped relation to the inner ends of the upper and lower bars and terminating in hooks, means connecting the upper and lower bars and the reticulated section to the flanges of the outer end bar, and means connecting the inner end bar and the reticulated section to the inner end portions of the upper and lower bars; the hooks of one member straddling the upper and lower bars of the other member, and the connections defined being formed by threaded bolts and nuts whereby on impairment of the screen section the same can be readily removed and 40 replaced with a new screen section.

In testimony whereof I affix my signature.

CHARLES B. McBRIDE.
